UNITED STATES PATENT OFFICE.

JOSEPH STOLZ, OF BERLIN-CHARLOTTENBURG, GERMANY, ASSIGNOR TO WESTING-
HOUSE ELECTRIC & MANUFACTURING COMPANY, A CORPORATION OF PENNSYLVANIA.

LEADING-IN BUSHING FOR HIGH VOLTAGES.

Application filed March 31, 1927, Serial No. 179,896, and in Germany November 6, 1922.

My invention relates to leading-in bushings for high voltages.

It is well known to construct leading-in bushings for high voltages of insulating 5 tubular members or shells made of porcelain, repelite, stoneware and the like insulating material, the internal spaces of which are filled with oil compounds or the like. It is also known to insert metallic partitions, 10 for instance concentric tubes, into such oil spaces, which serve the purpose to affect the distribution of the field of the bushing. This purpose is, however, in this way attained in a very imperfect manner only.

15 My invention relates to a bushing, insulator or duct in which the concentric insertions are not cylindrical but are bent towards the inner wall of the bushing or duct in any suitable manner. The edges of these curved 20 insertion members are so spaced from one another, that the distribution of the field upon the outer surface of the insulator is attained in the desired manner. The field may, for instance, be distributed uniformly 25 over the surface of the bushing, so that the equipotential surfaces run uniformly around the bushing.

In the drawing affixed hereto, in which 30 an embodiment of my invention is shown by way of example, Figure 1 is a longitudinal sectional view and Fig. 2 is a view taken substantially along the line II—II of Fig. 1.

In the drawing which illustrates my improved bushing or duct, *a* is the shell of the 35 bushing constructed of any suitable insulating material, *b* the conductor or connecting bolt, and *c* and *d* metal end caps closing the insulating shell or tube at the top and at the bottom. In the space between said bolt 40 and the shell are located the partitions *e*. These partitions may, for instance, be formed as rotation bodies which are directly adapted to the desired course of the equipotential surface. It will be understood, however, 45 that these partitions may equally well consist of cages constructed of wire or of metal strip and need not necessarily be continuous rotation bodies.

In order to avoid undesired radiations 50 owing to excessive density of power lines at the sharp edges of the partitions, they may preferably be provided with curled or beaded edges. In order to keep the metallic partitions or intermediate layers at the correct

insulating distance apart in the axial direction, distance pieces *f* are according to my invention provided between adjacent edges.

To enable the filling medium to fill up the hollow spaces completely, partitions or intermediate layers produced as solid rotation 60 bodies are provided with perforations or recesses on the circumference. To prevent contact between the metallic partitions and the inner partition and the connecting bolt *b*, barrier members or tubes *g* of insulating material 65 may be placed between them.

h is a flange for securing the bushing to the cover of the apparatus and *i* an electric connection of the outermost concentric 70 insertion *e* with said flange *h*.

Various modifications and changes may be made without departing from the spirit and the scope of the invention, and I desire, therefore, that only such limitations shall be placed thereon as are imposed by the prior 75 art.

I claim as my invention:—

1. In a bushing for high voltages in combination, an insulating tube, a plurality of 80 concentric metallic insertion members with diverging outer ends located in said tube, distance pieces for the ends of said members, caps at both ends of said tube, and a connecting bolt extending from end to end of said tube.

2. In a bushing for high voltages in combination, an insulating tube, a plurality of 85 concentric metallic insertion members with diverging outer ends located in said tube, distance pieces on said insulating tube for the ends of said members, caps at both ends of said tube, and a connecting bolt extending from end to end of said tube.

3. In a bushing for high voltages in combination, an insulating tube, a plurality of 90 concentric metallic insertion members with diverging outer ends located in said tube, insulating barrier members for the central portions of said members, distance pieces 100 for the ends of said members, caps at both ends of said tube, and a conductor extending from end to end of said tube.

4. In a bushing for high voltages in combination, an insulating tube, a plurality of 105 concentric metallic insertion members with diverging outer ends located in said tube, insulating barrier members for the central portions of said members, distance pieces

upon said insulating tube for the ends of said members, caps at both ends of said tube, and a conductor extending from end to end of said tube.

- 5. In a bushing for high voltages in combination, an insulating tube, a plurality of concentric metallic insertion members with diverging outer ends with curled beaded edges located in said tube, distance pieces upon said insulating tube adapted to keep the ends of said insertion members apart, caps at both ends of said tube, and a conductor extending from end to end of said tube.
- 6. A condenser bushing of substantially uniform cylindrical shape including concentric inner conducting layers having cylindrical portions disposed in predetermined radial relation to divide the voltage gradient along a radius of the bushing in predetermined steps, said layers being of successively different lengths and having ends of sub-

stantially the same diameter along, and adjacent to, the outer surface of the bushing to divide the voltage gradient of said surface into similar steps. 25

7. A condenser bushing of substantially uniform cylindrical shape including concentric inner conducting layers having cylindrical portions disposed in predetermined radial 30 relation to divide the voltage gradient along a radius of the bushing in predetermined steps, said layers being of successively different lengths and having rounded ends of substantially the same diameter along, and adjacent to, the other surface of the bushing to divide the voltage gradient of said surface into similar steps and to prevent concentration of electrostatic stresses at said ends. 35

In testimony whereof, I have hereunto subscribed my name this 28th day of February, 1927.

JOSEPH STOLZ.
